(57) **CLAIM**

The ornamental design for an elastomeric multi-tip eyeglass retainer connector, as shown and described.

DESCRIPTION

FIG. 1 is a perspective view of an elastomeric multi-tip eyeglass retainer connector;

FIG. 2 is a top view of an elastomeric multi-tip eyeglass retainer connector; and,

FIG. 3 is a side view of an elastomeric multi-tip eyeglass retainer connector.

The broken lines shown in FIGS. 1-3 are for illustrative purposes only and form no part of the claimed design.
